PROCESS FOR MAKING HEATING ELEMENTS

Earl K. Clark, Mansfield, Ohio, assignor to Westinghouse Electric & Manufacturing Company, East Pittsburgh, Pa., a corporation of Pennsylvania

Application February 18, 1939, Serial No. 257,167

2 Claims. (Cl. 201—67)

My invention relates to electric heaters and more particularly to methods of making a preformed ceramically insulated heater for a flat-iron or the like.

The general process of compacting a cementitious or refractory insulating material about an electrical resistor is well known to the art. However, due to the application of considerable pressure upon the insulating material during the process, it has been practically impossible to produce an unsheathed heater in which the resistor is formed from a helical coil. This difficulty has been caused by the coil shifting under the compacting pressure. Further, it has been practically impossible to get a uniform distribution of the insulating material inside the coil. In addition, the difficulties of getting the insulating material within a coiled resistor are considerably increased with a heating element formed in an elliptical helical manner, especially so, when the long axis of the helix is mounted in a vertical position.

It is, therefore, an object of my invention to provide a method of making a heating element having an elliptically coiled resistor and a uniformly compacted cementitious insulating material located within and about such coil.

A further object of my invention is to provide a method of making a preformed ceramically insulated heater for flatirons, or the like, which eliminates the necessity of handling cement in the vicinity of the finished and polished iron sole plate.

A further object of my invention is to provide a method of producing a heating element having a ceramic insulating material pressed around a coiled resistor without distorting such resistor.

Another object of my invention is to provide a method of producing a ceramically insulated heater in which the resistor is mechanically retained within the insulation so as to be centrally located therein and which will not shift its position upon applying the final compacting pressure.

Still another object of my invention is to provide an efficient, economical method of producing a ceramically insulated pre-formed flat-iron heater and of measuring the quantity of insulating material required.

Other objects of my invention will either be pointed out specifically in the course of the following description of a method of forming a device embodying my invention, or will be apparent from such description.

In the accompanying drawings:

Figure 1 is a perspective view of a flatiron sole

plate in which a heating element embodying my invention is located.

Fig. 2 is a partial elevational and sectional view of an illustrative press for making the heating element embodying my invention;

Fig. 3 is a perspective view of the heating element embodying my invention; and

Figs. 4, 5, 6 and 7 are transverse sectional views illustrating the press in various operating positions.

Referring to the accompanying drawings, I illustrate a method of producing a ceramically insulated heater 10 which is made in a general manner substantially as follows: Placing a loosely elliptically coiled resistor 12 in a die structure 13 on a mechanical holding device 14 within a slot 16, filling the slot 16 on one side of the resistor with insulating material 18, compacting the insulating material, inverting certain parts of the structure and placing additional insulating material upon the outer side of the resistor, and finally compacting the whole heating element.

More specifically, the die structure 13 comprises, in this instance, a first stripper plate or holding device 14, main forming dies 20 and 22, a second stripper plate 24 and a pressure die 26 which is adapted to be inserted between the forming dies 20 and 22 and within the slot 16.

The first stripper plate 14 comprises a main body portion, a plurality of upwardly extending bosses 28 and an upwardly extending holding portion 30. The upwardly extending bosses 28 cooperate with recessed portions 31 in the main forming dies 20 and 22, so as to position and retain such forming dies in a given fixed location and an upwardly extending holding portion 30. The upwardly extending holding portion 30 is substantially the same shape as one-half of the heating element 10 to be formed and is adapted to extend upwardly between the main forming dies 20 and 22 within the slot 16 formed therebetween. The forming dies 20 and 22 are thus retained in a given position and in conjunction with holding portion 30, determine the configuration of the heating element to be formed. In this instance, the slot 13 therebetween is approximately the same shape as the slot 11 in the flat-iron sole-plate 15.

The upwardly holding portion 30 of the stripper plate 14 has a grooved slot 32 located substantially in the middle of the upper surface thereof. The grooved slot 32 is substantially the same width as the external minor axis of the elliptically coiled resistor 12 and has a depth substantially one-half the external major axis of

such resistor. The groove 32 is thus capable of retaining the resistor 12 in a vertical position at substantially the middle of the slot 16 and permits only substantially the upper half of the resistor to be exposed for a purpose hereinafter described. However, it is to be understood that the resistor 12 may be retained within the die structure by any other suitable holding device.

The vertically extending slot 16 formed between the forming dies 20 and 22 is substantially the same width and approximately the same shape as that desired of the finished heater 10. However, the vertical height of such slot is considerably greater than that of the height of the finished heater 10. In this instance, the height of the slot 16 is of such value as to permit it to be used as a measuring device for the insulating material to be placed therein, substantially as hereinafter described.

The second or other stripper plate 24, located at the bottom of the die structure in Figs. 6 and 7, is substantially the same shape as the first stripper plate or holding device 14 and has a plurality of bosses 29 which cooperate within corresponding apertures 33 within the dies 20 and 22, and a holding portion 34.

The holding portion 34 of the second stripper plate 24 is somewhat shorter than the holding portion 30 of the lower stripper plate 18. However, holding portion 34 of plate 24 is substantially as long as the distance the pressure die 26 extends into the slot 16 during the first compacting operation. Accordingly, it is obvious that after the pressure die 26 has compacted the first portion of cementitious insulating material placed within the slot 16, the upper stripper plate 24 may be located upon the forming dies 20 and 22 with the holding portion 34 contacting the flat upper surface of the compacted insulating material, substantially as hereinafter described.

The pressure plate die 26 of the die structure 13 has a downwardly extending die portion 36 which is substantially the same shape as the slot 16 so as to freely extend therein as the die is forced downwardly.

The die structure 13 may be operatively associated with a pressure applying device or press 38 which is illustratively shown in Fig. 2. The press 38 includes a base plate 40 and a vertically moving pressure-applying member 42. The pressure device or press 38 is adapted to supply a relatively large pressure to the cementitious insulating material located within the slot 16 by means of the pressure die 26 which is rigidly attached to the vertically moving member 42. The base plate 40 has an undercut or depressed portion 41 which is substantially the same shape as the stripper plates 14 and 24. This portion 41 thus permits the plates 14 and 24 to be accurately centered thereon with respect to the pressure die 26.

The cementitious refractory ceramic insulating heater 10 is constructed in accordance with my invention substantially as follows: the die structure 13 is operatively associated with the pressure device 38 by having the pressure die 26 attached to the vertically moving member 42 and by having the first stripper plate 14 located and centered upon the base plate 40 within the depressed portion 41. The main forming dies 20 and 22 are then positioned upon the first plate 14, whereupon the vertically extending slot 16 is located therein (see Fig. 2). The elliptically coiled resistor 12 is then positioned within the

groove 32 upon the holding portion 30 of the holding device 14 in the slot 16. The resistor 12 is thus positioned at substantially the midpoint of the slot 16 with the main axis thereof located in a vertical position. The cementitious ceramic insulating material 18 is then put in and just fills the slot 16, the slot 16 thus acting as a measuring device. In other words, the insulating material 18 is located within the slot 16 so as to just fill such slot (see Fig. 4). Inasmuch as the insulating material is substantially in a powdered form it is obvious that such material will be evenly disposed within the loosely coiled resistor and about the upper portion thereof. The pressure device 38 is then actuated so that the moving member 42 thereof will force the pressure die 26 downwardly. The die portions 36 thereof will then enter into the slot 16, engaging the insulating material 18 and preliminarily compacting it into a relatively solid mass. Inasmuch as the insulating material is evenly distributed within and around the upper portion of the resistor 12, it is obvious that the pressure applied to the insulating material 18 will then evenly compact it to a uniformly dense mass within the resistor 12 and about the upper portion thereof (see Fig. 5).

The grooved slot 32 located in the holding portion 30 of the first holding device 14 being substantially the same shape as the lower half of the resistor 12, retains the resistor in a fixed vertical position, during the compacting step, insuring a uniform distribution of the compacted insulating material entirely within the coils of the resistor and limits the amount of insulating material being located about the outer surface of the coil.

In this instance, the horizontal plane of the top face of holding portion 30, which determines the lowermost point of the insulating material 18 prior to and during the first compacting step is positioned at substantially the mid-point of the vertical or major axis of the resistor 12 (see Figs. 5 and 6). In addition, the material is located within the coils of the resistor 12. However, the insulating material placed upon and within the resistor during the first step of production need not completely fill the resistor, and the dividing line need not be positioned exactly as described so long as the compacted material is capable of retaining the coil in a fixed position during the remaining steps of the process.

The pressure die 26, by reason of the movable action of the moving member 42 is then removed from the main forming dies 20 and 22. The second stripper plate 24 is then located or positioned upon the main forming dies 20 and 22 with the holding portion 34 extending into the slot 16 and resting upon the upper surface of the compacted insulating material 18. The die structure 13 including the second and first stripper plates 24 and 14, respectively, and the main forming dies 20 and 22 is then reversed or inverted so that the upper strip or plate 24 will be located at the bottom of the main forming dies 20 and 22. The "upper" or second stripper plate will then be positioned within the depressed portion 41 so as to again center the slot 16 with respect to die 26.

The "lower" or first stripper plate 14, which is now on top, is then removed, leaving the now upper portion of the slot 16 open (illustrated as 16a in Figs. 6 and 7). Additional insulating material 18 is then positioned within and just filling the exposed portion of the slot 16, which

again acts as a measuring device for the amount of insulating material required. The loose, uncompacted cementitious refractory insulating material 18a is then located upon the previously compacted insulating material 18 and about the now upper or remaining portion of the resistor 12. However, inasmuch as the inner space of the coil 12 has been previously substantially filled and compacted with insulating material, the newly added insulating material 18a cannot extend therein; but when the coil 12 has been only partially filled the additional or second portion of insulating material will fill the remaining space within such coil. The vertically moving pressure applying member 42 is then moved downwardly, causing the die portion 36 of the pressure die member 26 to extend into the slot 16 and compact the additional insulating material 18a (see Fig. 7).

The final compacting pressure in the step just described is substantially greater than the preliminary compacting pressure in the step previously described, inasmuch as the resistor 12 was already firmly positioned within the compacted insulating material 18 and will not move with respect to the outer edge thereof even though a relatively high pressure is applied. Accordingly, it follows, that the final pressure application may be of such value as to safely and satisfactorily compact the insulating material into a solid homogeneous mass about and within the helically coiled resistor.

It is to be understood that the coiled resistor may be of any desired shape other than the preferred elliptical section used herein. However, it is to be understood that the insulating material used in the first compacting step is to be located within as well as about the coils of such resistor so as to allow the resistor to be retained in a given fixed position while the initial pressure or compacting step is effected.

After having had sufficient pressure applied thereto, the main forming dies 20 and 22 are removed from the second stripper plate 24, which at this stage is located at the bottom. The heating unit 10 may then be moved from the holding portions 34 of the plate 24 and placed in any suitable baking oven (not shown) or may be placed directly within the slot 11 of the flatiron sole plate 15 shown in Fig. 1.

It is obvious that when forming a heater utilizing a coiled resistor, in the manner hereinabove described, such resistor is retained in a given fixed position, the insulating material is evenly distributed throughout the heater, and

5 because of the even distribution of insulating material, a final compacting pressure may be applied which will form a solid homogeneous insulating mass about and within the resistor without causing the resistor to shift therein.

10 It therefore follows that by using the two-step compacting process embodying my invention in which the resistor is centered and held in position until firmly embedded in the first portion of insulating material, such element, after having the second portion of insulating material placed thereon, may be subjected to a second pressure substantially greater than the first without causing the resistor to shift its position. In other words the process embodying my invention provides a method for centering and holding the resistor within the insulating material and eliminating electrical insulating faults in the final product.

15 20 Various modifications may be made in the method of forming the device embodying my invention without departing from the spirit and scope thereof, and I desire, therefore, that only such limitations shall be placed thereon as are 25 imposed by the prior art and the appended claims.

I claim as my invention:

1. The method of making an electrical heating element in which the resistor is in the form of a helical coil, which comprises encompassing a portion of the helical coil below a horizontal longitudinal plane therethrough to hold the coil in place, placing uncompacted insulating material within the entire coil but around only the unencompassed portion of the coil above said plane, compacting the insulating material around said unencompassed portion of the coil, inverting the coil and freeing the encompassed portion thereof, placing uncompacted insulating material around the freed and now upper portion, and compacting the additional insulating material.

2. The method of making a heating element in which the resistor is in the form of a helical coil, which comprises retaining the coil in a fixed position by contacting approximately the lower half 45 of its surface below the horizontal diametral plane thereof, placing insulating material within the coil and about substantially the uncontacted upper half of the coil above said plane, compacting the material about the uncontacted upper half 50 of the coil, freeing the coil from said contact, placing additional insulating material about the remaining half of the coil, and compacting such additional material.

EARL K. CLARK.
